CALCULATING MACHINE

Ernest Raetz, Detroit, Mich., assignor to Burroughs Adding Machine Company, Detroit, Mich., a corporation of Michigan

Application April 22, 1939, Serial No. 269,386

7 Claims. (Cl. 235—60)

This invention relates to calculating machines and more particularly to a machine which may be used for ordinary listing operations such as addition, subtraction, and the accumulation of positive and true negative totals, as well as for bookkeeping operations such as the posting of ledger sheets and the printing of a proof of the postings on a separate sheet.

There are of course many calculating machines at the present time which are in general capable of performing the foregoing types of work. Most, if not all, of these machines, however, are relatively large machines and require the services of specially trained operators. Many relatively small business organizations require or could profitably use a relatively small bookkeeping machine, particularly if the machine was readily convertible into an ordinary calculating machine adapted to the usual type of work for which these machines are employed. In such installations the machines are generally operated by operators not specially trained in the use of bookkeeping machines and who at best usually only operate the machine at infrequent periods. Therefore it is highly desirable, if not necessary, that small machines of this type be as fully automatic and as fool-proof as possible, so as to enforce proper operation and prevent misoperation.

It is an object of this invention to provide an improved calculating machine.

It is also an object of this invention to provide an improved calculating machine that is readily convertible from a straight adding machine to a bookkeeping machine.

It is a still further object of this invention to provide a bookkeeping machine in which proper operation thereof is automatically controlled and enforced.

Further objects and their resultant advantages will be apparent from the following description, particularly when taken in connection with the drawings, in which:

Figure 1 is a right side elevation of a machine with casing removed, embodying the principles of this invention and illustrating mainly the controls utilized for ledger posting and with the carriage in starting or column 1 position.

Fig. 1^a is a side elevation of the front portion of the machine omitted from Fig. 1.

Fig. 1^b is a right-side elevation of the upper rear portion of the machine showing particularly the paper carriage mounting, the platen line-spacing means and the normalizing means.

Fig. 2 is a right side elevation of the machine illustrating primarily main operating mecha-

nisms of the machine, most of the ledger posting controls being omitted.

Fig. 3 is a plan of a portion of the keyboard.

Fig. 4 is a rear elevation of a portion of the paper carriage and associated parts illustrating the carriage controls, the carriage being in column 1 position.

Fig. 4^a is a partial rear elevation of the machine showing particularly certain parts of the carriage controls.

Fig. 5 is an enlarged view of certain of the parts shown in Fig. 4 with the paper carriage in its column 6 position.

Fig. 6 is a detail view of another portion of Fig. 4 illustrating the parts in active position.

Fig. 7 is a partial right side elevation of the carriage control and result key mechanisms, the parts being in position with the carriage in the last or column 7 position.

Fig. 8 is a partial side elevation of the two motor bars, both being in raised or undepressed position.

Fig. 9 is an enlarged end elevation of the totalizer section of the machine.

Fig. 10 is a detail view of portions of the clutch mechanism.

Fig. 11 is a perspective view of a portion of the tabulating mechanism.

Fig. 12 is an illustration of a sample of ledger posting that may be performed in a machine embodying this invention.

Fig. 13 is an enlarged detail of portions of the upper part of the machine.

The invention is shown applied to a Burroughs portable machine which is on the market and the general features of which are well-known and shown in many prior patents. Only such portions of the machine as are associated directly with the present invention will be described in detail, reference being made to the Horton Patents Nos. 1,853,050 and 1,853,053, and to the Butler Patents Nos. 1,992,142 and 2,118,588 for details of those mechanisms embodied in the machine of the present invention but not involved directly with the present invention. It is to be understood, of course, that the invention can be incorporated in machines of other makes and types.

General calculating machine features

The machine is provided with a keyboard 1 having a plurality of banks of depressible amount keys 2, there usually being nine banks of nine keys each. The keyboard is also provided with a bank of control keys (Fig. 3) com-

prising a subtotal key ST, a total key T, a credit balance key Cr., a non-add key NA, a repeat key R, and an error key E.

The machine may be either hand operated or motor driven. The illustrated machine is a motor driven machine of the type shown in the Horton Patent No. 2,004,282 and is also provided with an add motor bar +M and a subtract motor -M for controlling a motor 5 and causing the machine to perform either addition or subtraction as described in the Butler Patents Nos. 1,992,142 and 2,118,588. Motor 5 actuates the main operating means by mechanism shown in the above Horton patent and drives the main drive shaft 6 first counterclockwise to give the machine a forward stroke of operation after which the shaft is returned clockwise to its original position, the latter movement being called the return stroke of operation. The two movements constitute what is generally known as the cycle of operation of the machine.

During the forward stroke of an amount-entering cycle a series of actuator racks 8 are released for upward movement under the influence of springs (not shown) until they are arrested in differential positions by engagement of the stop bars 9, pivotally connected to the racks, with the stems of the depressed amount keys. Each actuator rack carries a type bar 10 which is differentially positioned with its actuator rack. After the type bars are positioned a printing mechanism of which the hammers 11 are shown in Fig. 1, is operated to print the item, such as the amount entered or the total thereof, on a sheet of paper carried by the platen P which is supported by the traveling paper carriage C mounted upon a fixed guide rail 15 and constantly urged to the right by the coil spring 16 as will be explained later in greater detail. In other words, the carriage is spring urged to the left and is adapted to be manually returned to the right. The carriage is caused to tabulate from column to column and is controlled in its tabulating movements by a tabulating mechanism which will be described later.

One or more registering mechanisms may be provided for cooperation with the actuator racks, although only one registering mechanism or totalizer is shown in the illustrated embodiment of this invention. The engagement and disengagement of the register pinions is controlled by a pitman 20 which normally occupies the position shown in Fig. 2 in which position the register pinions are not engaged with the actuator racks. The pitman is moved rearwardly by means of a drive plate 21 rocked by the drive shaft 6, the drive plate having two studs 22 and 23 for this purpose.

During the forward stroke in adding operations the drive plate 21 rocks counterclockwise but the studs 22 and 23 do not engage any part of the pitman 20. However, the stud 23 passes a pawl 24 pivoted on the upper branch of the pitman and near the beginning of the return stroke stud 23 engages a shoulder on pawl 24 and moves the pitman 20 rearwardly which rocks the register pinions into engagement with the actuator racks. Near the end of the return stroke the stud 22 engages the hooked end 25 of the lower branch of pitman 20 and returns the pitman forwardly to rock the register pinions out of engagement with the actuator racks.

When the total key T or subtotal key ST is depressed a link 26 is moved downwardly which swings a pawl 27 pivoted on the lower branch of

the pitman 20 into the path of the stud 22. The depression of the total key T also depresses the forward hooked end of a pawl 28 pivoted on the upper branch of the pitman 20 and the depression of pawl 28 swings the pawl 24 out of the path of the stud 23. Accordingly when the drive plate 21 rocks counterclockwise during the forward stroke of the machine, the stud 22 engages the end of pawl 27 and the pitman 20 is moved rearwardly to move the register pinions into engagement with the actuator racks prior to their ascent. During their ascent the racks rotate the register pinions back to "0" position to take the total from the register pinions, in which position the pinions are arrested by the trip pawls as described in the Butler Patent No. 2,118,588. Near the end of the forward stroke of the machine if the total key T has been depressed, the stud 23 engages the hooked end of the pawl 28 and pulls the pitman forward again to rock the register pinions out of engagement with the actuator racks prior to the descent and thus leave the register pinions in "0" position.

Depression of the subtotal key causes the same results as explained above except that said key does not move the hooked end of the pawl 28 into the path of the stud 23 so that the pitman is not moved forward again at the end of the forward stroke. The result is that the register pinions remain in engagement with the actuator racks during their descent and the total is put back into the register pinions. Near the end of the return stroke the stud 22 engages the hooked end 25 of the lower branch of the pitman 20 and rocks the register pinions out of engagement with the actuator racks.

Depression of the non-add key NA causes its stem to engage and rock a lever 29 clockwise to a position where its lower cam finger 29a will be engaged by stud 23. Engagement of finger 29a by stud 23 will rock lever 29 farther and cause a stud 29b carried thereby to engage pawl 28 and rock the latter counterclockwise. Lowering of pawl 28 will rock pawl 24 clockwise so that its shoulder will not be engaged by stud 23 and the register pinions will not be moved into engagement with the racks 8 and no entry will be made in the register pinions. In other words, the machine is indexed for a non-add operation by depression of the NA key and the actual movement of the part is completed by power operated mechanisms. The machine may also be placed in non-add condition under control of the carriage as will be explained later.

Add-subtract registering mechanism

The registering mechanism that has been found preferable and which is illustrated in the present embodiment of the invention is of the "tumbling register" type, as illustrated in the Butler patents heretofore mentioned, and comprises two sets of interconnected register pinions. The lower set 30 is called the addition pinions and the upper set 40 is called the subtraction pinions, although in fact the two sets of pinions operate together to perform addition and subtraction.

The addition pinions 30 are rotatably mounted upon a shaft 31 and the subtraction pinions 40 are rotatably mounted upon a shaft 41. The two shafts are carried by a U-shaped tumbling frame 32 (Fig. 9) to which are fixed right and left stub shafts 33 journaled in a rockable register frame comprising two arms 34 fixed to a shaft 35 pivoted in the machine side frames (Fig. 9). The register frame 34 is rocked forward and backward to en-

gage and disengage the pinions with the actuator racks 8 by means of the pitman 20. As can be seen from Fig. 2, the pitman 20 is connected to a crank 36 fixed to a shaft 37. Also fixed to this shaft is a cam 38 having a cam slot engaging a roller 39 on one of the stub shafts 33. When the pitman 20 is moved rearwardly from the position of Fig. 2, the cam 38 cams the roller 39 forward and rocks the register frame counterclockwise to cause the register pinions that are in operative position to engage the actuator racks. When pitman 20 is pulled forwardly again the cam 38 together with a spring 39a (Fig. 2) turns the register frame clockwise to disengage the register pinions from the actuator racks.

For addition the tumbling register mechanism occupies a position with the addition register pinions 30 so positioned that they are engaged with the racks prior to their descent. In this condition the addition pinions 30 in banks where keys which have been depressed are rotated counterclockwise as the racks descend to thereby register additively.

For subtraction the tumbling register frame is tumbled and with the mechanism in this position the subtract pinions 40 are engaged with the racks prior to their descent and the descent of the racks will rotate the subtraction pinions 40 counterclockwise in those banks where keys have been depressed.

Counterclockwise rotation of the subtract pinions 40 will rotate the addition pinions 30 clockwise, i. e., in a reverse direction from addition. Accordingly subtraction and addition are thus performed by rotating the pinions 30 in opposite directions.

Both positive and true negative totals may be taken from the registering mechanism without the necessity of giving the machine a spacing stroke and provision is also made for locking the register pinions against accidental turning while they are being tumbled, all as described in the Butler Patent 2,118,588 to which reference is made for further disclosure of the foregoing mechanisms.

Transfer mechanism

The registering mechanism is of course supplied with a suitable transfer mechanism of the type shown in the Horton Patent 1,853,053 suitably modified to cooperate with two sets of register pinions instead of one. That is, the trip pawls 43 are provided with two cam noses instead of one in order to adapt the mechanism to the two sets of register pinions. Furthermore, the pawls are operated through the set of pinions that is out of active position instead of the pinions that are in active position. This mechanism is also illustrated and disclosed in the Butler Patent 2,118,588 to which reference is made for a detailed description of the transfer mechanism.

Positive total taking

Positive totals are taken in the manner substantially the same as in the Horton and Butler patents heretofore referred to. Depression of the total key T moves link 28, Fig. 2, downward which moves pawl 27 on pitman 20 into the path of the stud 22 so that the pitman 20 moves rearwardly at the beginning of the forward stroke and thereby rocks the registers into engagement with the actuator racks at the beginning of the forward stroke. If the registering mechanism is in add position, and contains a positive total, the registering mechanism moves into engagement in the

regular manner, that is, the add pinions 30 come into engagement with the actuator racks. If, however, the registering mechanism is in subtract condition because of a previous depression of the —M motor bar, but contains a positive total, the registering mechanism is automatically tumbled to add condition as disclosed in said Butler patents so that the add pinions 30 come into engagement with the actuator racks. Then as the machine starts to operate the actuator racks rise and the add pinions are rotated in a direction reverse to that in which they have been rotated in the entry of positive items in the register pinions until they are arrested in their "O" positions by the wide faced teeth of the register pinions engaging the trip pawls, as described in more detail in the Butler Patent No. 2,118,588.

Negative total taking

True negative totals are taken in much the same way as positive totals, that is, by depression of the same total key T and by giving the machine a single stroke of operation, but negative totals are taken with the subtraction pinions 40 in engagement with the actuator racks as distinguished from the addition pinions 30.

Assume that a negative total has been created by subtracting a larger number from a smaller one. The machine has been placed in subtraction condition by depression of the —M motor bar to perform the subtraction operation and it normally remains in this condition at the end of the operation. Assume that the negative total is to be taken with the parts in this condition. The registering mechanism has been tumbled so that the subtraction pinions 40 are in position to engage the actuator racks. It will of course be assumed that the "fugitive 1" has been inserted so that no error of a unit occurs.

Depression of the total key T moves the lever 50 (Fig. 2) so as to position the end of the pawl 51 in the path of the pin 52 on the crank 53 so that as the machine is operated and the register moves into engagement with the actuator racks the ball 54 (Fig. 9) is rocked to block all the trip pawls 43 against movement and cause them to act as stops to arrest the register pinions in "O" position. The register pinions move into engagement with the actuator racks and as the racks descend they rotate the subtraction pinions clockwise. The result is that the actuator racks in those orders which are movable will move and set the type bars in corresponding position and the correct negative total will be printed.

If it should happen that after a negative condition occurs another item is added in the register pinions which item is, however, too small to change the negative total to a positive total the machine might be in addition condition at the end of operations but a negative total would still remain in the registering mechanism. Of course it is necessary in order to take a negative total that the registering mechanism be in subtraction condition and accordingly the registers must be tumbled before a negative total can be taken. This tumbling of the register mechanism occurs automatically as is described in the Butler Patent 2,118,588.

"Fugitive 1"

As previously mentioned it was assumed that a "fugitive 1" had been entered in the register pinions when a negative total occurred. The "fugitive 1" mechanism employed is similar to that disclosed in the Butler Patent 2,118,588 to which reference is made for a disclosure of this

mechanism. It will be sufficient to state here that the "fugitive 1" is automatically inserted only when the register is changed from positive to negative condition and vice versa. It is not inserted every time the machine changes from addition to subtraction or vice versa; it is not inserted every time the pinion of highest order passes through "0" and it is not inserted when the capacity of the register is exceeded in either a positive or a negative direction. It is, however, automatically inserted at the proper time, namely, when the total changes from positive to negative and vice versa.

Carriage tabulation

As previously stated the present machine is provided with a traveling paper carriage C which is automatically moved in one direction, is controlled in such movement by operation of the machine, and is returned manually to the right. The carriage is moved in tabulating direction from column to column from right to left during each operation of the machine by the coiled tension spring 16 (Fig. 1) one end of which is attached to a stud 60 projecting from the right end of the frame from which the spring extends to the left side of the stationary machine frame where it passes around a roller 61 after which the spring returns to the right where it is fastened to a stud 62 projecting from the carriage. This provides a constant and uniform tension or urge on the carriage tending to move the latter to the left.

The carriage is controlled in tabulating movement to the left so as to tabulate one column at each machine operation through the medium of a stop bar 65 (Figs. 1 and 4) supported at the rear of the carriage which bar is notched preferably at each letter space position to adjustably receive a plurality of stops 66 adapted to engage a fixed stop 67 (Figs. 4 and 11) to arrest the carriage in different columnar positions. The fixed stop 67 is slidably supported by studs 68 upon a blade 69 pivoted on a shaft 70 supported from the carriage frame. The fixed stop may thus slide horizontally upon its studs 68 and may rock into and out of engagement with the adjustable stops due to the pivotal movement of the supporting blade. The fixed stop 67 is normally urged to the left looking at the rear of the machine by a lever 72 (Fig. 4) which engages an upturned lug 73 (Figs. 4 and 11) on the stop 67, the lever being pivoted at 74 and urged counterclockwise looking at it from the rear by a spring 75. The upper end of lever 72 is connected by a link 76 to a dash pot 77 to cushion the fixed stop, and thus ease the blow when the adjustable stop 66 engages the fixed stop 67.

The supporting blade 69 is normally urged counterclockwise (Fig. 11) by a spring 78 which engages one arm of a crank 79 pivoted at 80, the other arm of which has a stud and fork connection 81 with an arm 82 of the supporting plate. The plate is rocked against the tension of spring 78 so as to disengage the fixed and adjustable stops at each machine operation by a pawl 85 pivoted on a stud 85^a projecting from the rear end of a slide 86 (Figs. 13 and 11) and urged counterclockwise by a spring 87. Slide 86 has a depending arm 88 which has a hooked connection with a stud 89 carried by one arm of a yoke 90 pivoted at 91 and operated at each machine operation. This yoke 90 is the usual yoke employed by the Burroughs portable machine as shown in the Horton Patent No. 1,853,-

5050, yoke 90 being yoke 279—280 of the latter patent, for controlling paper feed and the printing latches. As described in these earlier patents this yoke is first moved clockwise and then returned counterclockwise on its pivot 91 at each machine operation. The pawl 85 is adapted to engage a lug 92 depending from the blade 69 and is so shaped that during the forward machine stroke during which stroke the slide 86 is moved rearward, a notched shoulder 93 (Fig. 11) passes under the depending lug 92 and has no effect on the blade and fixed stop 67. During the return stroke of the machine slide 86 moves forwardly, to the left in Fig. 11, and shoulder 93 engages and rocks blade 69 and the fixed stop 67 clockwise (Fig. 11) to disengage or release the fixed stop from the adjustable stop 66 thus releasing the carriage and permitting it to tabulate into the next columnar position. The rear end 10 of pawl 85 is so shaped that after the blade and fixed stop have been rocked out of engagement with the adjustable stop the pawl is cammed clockwise by a stud 95 carried by a rearwardly projecting arm 96 of the normalizing lever which will be described later. As the pawl is cammed clockwise it releases the blade and permits it to be returned counterclockwise by its spring 78 so as to be in position to stop the carriage in the next columnar position by engaging the next adjustable stop 66.

15 The blade 69 and fixed stop 67 and accordingly carriage tabulation may be controlled manually by means of a lever 97 fixed to a ball 98 that extends the full width of the carriage and is journaled in the side frames of the carriage. This ball has a depending blade 100 in position to engage a stud 101 carried by the forward arm of the crank 79 so that, regardless of the position of the carriage, hand lever 97 may be rocked and will in turn cause the depending blade 100 to engage the stud 101 and rock the blade 69 and fixed stop out of engagement with the adjustable stops.

Platen line spacing

20 The platen may be line spaced manually by turning the usual twirlers as is customary and it is also arranged to be automatically line spaced in a predetermined columnar position or positions. For this purpose the platen is provided with the usual ratchet wheel 110 (Figs. 1 and 1b) together with a spring urged detent 111 and spacing pawl 112 the latter being carried by a shaft 113 that extends across the entire width of the carriage and is supported at each end by levers 114 fixed to a shaft 115 pivoted in the carriage side plates. Line spacing is accomplished by rocking shaft 113 which carries the spacing pawl and this is accomplished in the usual manner by a lever 116 which has a forked end engaging the shaft 113 at approximately the center of the machine. Lever 116 extends downwardly through the top plate of the machine (Fig. 13) and is attached to the yoke 90. Accordingly each time the machine is operated and the yoke 90 is rocked the spacing pawl 112 is moved rearward during the forward machine stroke and returned forward to space the platen during the return machine stroke. This line spacing is accomplished in a manner similar to that disclosed in the Horton Patent 1,853,050, the present lever 116 being arm 331 of the Horton patent.

25 The extent or degree of line spacing is controlled (Fig. 1b) by a shield 120 formed integrally with a lever 121 pivoted at 122 to the carriage

frame. The upper end of lever 121 is connected by a link 123 to an arm 124 fixed to a shaft 125 which shaft extends the full width of the carriage as shown in Fig. 4. Link 123 is urged to the right (Fig. 1b) and consequently arm 124 and shaft 125 are urged counterclockwise and lever 121 clockwise by a spring 126. The shaft 125 carries a depending blade 127 which is adapted to engage a roller stud 128 (Figs. 1b and 4) carried by an arm 129 which extends downward (Fig. 4) and terminates in a yoke 130 pivoted at 131.

The traveling paper carriage carries a roller 132 (Figs. 1b and 4) which is positioned to the rear of arm 129 and is adapted to engage and rock the arm 129 forward when passing the arm which, in turn, rocks the control member 120 counterclockwise. The arrangement is such that during ordinary operations of the machine, while the carriage is tabulating from column to column, spring 126 (Figs. 1 and 1b) urges lever 121 clockwise so that the shield 120 will prevent the spacing pawl 112 from engaging the ratchet 110, thus preventing a line spacing movement of the platen. When the carriage arrives in the last columnar position in the illustrated machine, the control roll 132 operates the arm 129 which, in turn, rocks the blade 127 and moves the shield counterclockwise away from the pawl 112 and allows the line spacing pawl to engage the ratchet and line space the platen after the amount has been printed in the last column. This positions the paper for the next line of printing when the carriage again tabulates from right to left.

Carriage control of non-add

For automatically conditioning the registering mechanism for a non-add operation with the carriage in column 2 position, the carriage carries a roll 133 (Fig. 7) which, when the carriage is in column 2, engages and rocks a yoke 133a, thus raising a link 134 which is guided on a stud 206 and in turn rocks counterclockwise a lever 135 (Figs. 1, 2 and 7) pivoted at 203. The lever 135, through a spring 136, rocks counterclockwise a three-armed lever 137 (Fig. 2) also pivoted at 203. The forward arm 138 of the latter lever engages the stud 29^b of lever 29 and rocks the latter clockwise the same as if the non-add key NA were depressed, thus conditioning the register mechanism for a non-add operation. Lever 135 also controls the cipher split mechanism in a manner well understood in this art and not described herein.

Carriage control of motor bar selection

As previously stated, the machine of this invention is so constructed that proper manipulation of the various control keys and motor bars is enforced to insure proper operation of the machine even though operated by inexperienced operators. In other words, it is practically impossible to misoperate the machine, when used for bookkeeping purposes. More specifically the operator is prevented from selecting or depressing the wrong keys and is thereby prevented from selecting the wrong machine operation or program in each of the various columnar positions of the paper carriage. The machine is so constructed that as the carriage tabulates into each columnar position the carriage conditions various devices so that the operator is only permitted to select and depress the proper control keys and motor bars consistent with the form or program for which the machine is intended. Accordingly, even though different and inexperienced operators

may use the machine the operators must use the machine properly and cannot make wrong entries even though they are inexperienced and unfamiliar with the machine. In order to accomplish this degree of safety assurance in operation, carriage controlled interlocks are provided whereby the motor bars and control keys must be depressed in proper order or sequence in accordance with the columnar position of the carriage.

Considering first control of the motor bars it will be necessary to describe their construction and functions and then describe the control thereof. In the illustrated embodiment the add motor bar +M is fixed to a sliding stem 140 (Fig. 8) mounted for substantially vertical movement on stud and slot connections 141. The stem 140 is formed with a forwardly and laterally projecting lug 142 in position to engage the forwardly projecting finger 143 of the clutch control member 144 mounted for substantially vertical movement on stud and slot connection 145 and on the clutch control shaft 146, the member being forked at its lower end to straddle the clutch control shaft. The clutch member is urged upward by spring 147. This clutch control shaft 146 is the usual clutch control shaft such as the shafts shown at 7 and at 239 in the Butler Patents Nos. 1,992,142 and 2,118,588 respectively and at 56 in the Horton Patent No. 2,004,282 which shaft when rocked clockwise by depression of the motor bar releases the drive clutch and starts the motor to operate the machine as disclosed in said patents. In the illustrated machine, however, the motor bar and member 144 instead of directly rocking the shaft 146 merely releases the shaft for rotation. A rearwardly extending arm 148 of member 144 (Figs. 1 and 8) carries a stud 149 which when depressed engages the lower arm of a three-armed latch 150 pivoted at 151, and rocks a latch member counterclockwise against the action of its spring 152. This removes its upper notched end from a square stud 153 on the upper end of an arm 154 fixed to the clutch control shaft 146 and releases the arm 154 and clutch shaft 146 for rotation clockwise (Fig. 1) by its spring 155 to cause an operation of the machine. The foregoing construction eliminates any load upon the motor bar due to the fact that depression of the motor bar does not have to rock the clutch control shaft but merely releases a latch whereby the shaft may be rocked by a spring.

The motor bar is latched in depressed position for the full cycle of operation by pivoted latch 160 (Fig. 1) urged counterclockwise by its spring 160a and notched at its lower end to engage a square stud 161 projecting from the stem 140 and having its upper end formed with a laterally projecting lug 162 positioned to engage a release slide 163. Slide 163 extends rearwardly where it is connected by a stud 164 to another slide 165 (Fig. 1) which is the usual locking slide for controlling the result keys, which slide extends forwardly and at its forward end terminates in a hook 166 (Fig. 1a) which engages the upper end of a lever 167. Lever 167 is pivoted on a cross rod 168 supported in lugs (not shown) depending from members of the keyboard assembly and has a lower forked end 169 which engages a control rod 170 carried by two arms 170a supported from cross rod 168. Arms 170a and control rod 170 are urged rearwardly by a spring 170b. A lower slide 171, urged rearwardly by a spring (not shown), is supported with its forward end in position to engage a roller 172

on rod 170 and its rear end 173 in position to engage the stud 22 (Fig. 1). In each cycle of operation of the machine the slide 171 is moved rearwardly by its spring and then returned forwardly by the roller stud 22 to rock lever 161 and move slide 165 rearwardly to release all depressed keys as is described more fully in the Butler Patent 1,992,142 and Horton Patent 1,853,050; the slide 165, lever 167, slide 171 and stud 22 being slide 180, lever 196, slide 201, and stud 200 respectively of the Horton patent. As the slide 165 for the control key bank is moved rearwardly, it moves the slide 163 rearwardly and the latter trips the latch 169 to permit the depressed motor bar to restore.

The clutch control shaft 146 is automatically restored in a counterclockwise direction (Fig. 10) at each machine operation, as described in the Horton Patent 2,004,282. In order to prevent continued operation if the motor bar is held depressed after one machine operation has been completed an auxiliary latch 176 (Fig. 1) is pivoted at 151 and has an upper notched end which under certain conditions falls into position to engage the stud 153 on the arm 154 fixed to shaft 146. This latch has a forwardly extending arm 177 formed with a lug 178 on its forward end in position to engage the control member 144 so that when the latter is in normal or raised position it holds the auxiliary latch 176 in clockwise or inactive position. However, when the motor bar is depressed member 144 is lowered and the auxiliary latch 176 is allowed to rock counterclockwise so that it is in position to engage its shoulder under the stud 153 the moment the stud and arm 154 are returned which, as previously stated, occurs at each machine operation. The auxiliary latch therefore holds the arm 154 and shaft 146 in counterclockwise or normal position until the motor bar and the control member 144 are released and raised by their springs and the control member 144 first permits the latch 169 to position its shoulder under the stud 153 and then moves the auxiliary latch 176 to disengage its shoulder from the stud 153.

Depression of the add motor bar +M accordingly releases the clutch shaft and permits an adding operation of the machine which is a normal operation as explained in more detail in the heretofore mentioned Butler patents.

In addition to the add motor bar +M, the illustrated machine is also provided with a subtract motor bar -M (Fig. 8) fixed to the upper end of a stem 181 mounted for substantially vertical movements by stud and slot connections 182, the bar being urged upward by spring 183. The subtract bar stem 181 has a rearwardly projecting lug 184 overlying a forwardly projecting lug 185 formed on a vertical irregularly shaped slide 186 which lug in turn overlies a laterally projecting lug 188 formed on the clutch control member 144. Accordingly when the subtract motor bar -M is depressed its lug 184 engages lug 185 which, in turn, engages lug 188 and lowers the clutch control member thus initiating a machine operation.

The slide 186 has a rearwardly projecting hooked arm 189 which engages a stud 190 carried by one arm of a lever 191, the latter controlling the subtract mechanism of the machine. Thus when the subtract motor bar is depressed it automatically initiates a machine cycle and conditions the machine for a subtract operation, that is, to cause a tumbling of the add subtract

registering mechanism from add to subtract position.

The subtract motor bar is latched in depressed position by a latch 192 (Fig. 1) similar to latch 169 and engaging a stud 193 on the subtract motor bar stem. The subtract motor bar latch is released by the same slide 163 that releases the add motor bar.

The arm 191 is part of a yoke member 400 (Fig. 1) having a downwardly extending arm 401 connected to the rear end of a link 402, the forward end of which is connected to a lever 403 pivoted on a stud 404 carried by the machine frame. A spring 405 connected at one end to the lever 403 urges the latter counterclockwise, the link 402 forwardly and the yoke 400 clockwise to the adding position shown in Fig. 2. The yoke 400 carries a stud 406 which engages in a slot in one arm of a yoke 407 which corresponds to the yoke 51 of the Butler Patent 2,118,588 and controls the addition and subtraction condition of the registering mechanism in the same way as disclosed in said patent. However, in the present machine, the yokes 400 and 407 do not remain in subtract position after a subtraction operation of the machine but are returned to the adding position of Fig. 2 when the slide 186 restores to its normal position shown in Figs. 1 and 8 so that if the machine is next operated by depression of the add motor bar which has no operative connection with the slide 186, the registering mechanism will, nevertheless, be tumbled to adding condition.

As previously stated the machine of this invention is intended to be used for cross tabulation posting in which each columnar position may represent a different type of machine operation in the program of operation and one of the objects of the machine is to provide a carriage control of motor bar selection which, although it does not select the motor bar or mechanism to be operated by depression of the motor bar, does, however, cause the proper motor bar and mechanism to be released or operable and therefore forces the operator to select the proper motor bar for depression in each of the columns. If the operator attempts to depress the wrong motor bar, that is, one that will conflict with the definite program provided for, he will find this motor bar locked against depression and will therefore have a warning that he is not properly operating the machine.

The means for selectively locking the two motor bars comprises a two-armed pendant lever 195 pivoted at 196 (Figs. 1 and 7), the two ends terminating in lugs 197 and 198, the former being adapted to engage in a notch in the forward edge of the add motor bar stem 140 and the latter being adapted to engage in either a rear notch in the add motor bar slide or in either of two notches in the forward edge of subtract motor bar slide 181 depending upon the position of the lever 195. The arrangement of lugs and notches is such that the lever may be positioned to engage and lock neither or either motor bar stem or both motor bar stems. The pendant lever is pivotally connected to the forward end of the link 200 the rear end of which carries a stud 201 engaging in a slot in the lower vertical arm of a crank 202 pivoted at 203 to the machine frame. A spring 201a yieldingly holds the stud 201 in the rear end of the slot in the arm 202. The other end of the arm of crank 202 extends rearwardly and terminates in a stud and slot connection 204 with a forwardly

projecting arm of a vertical link 205 mounted for sliding movement upon the stud 208, the upper end of which link is connected to one arm of a yoke 207 pivoted at 208, the other arm of which yoke extends upwardly in position to engage a control roll 209 carried by the traveling paper carriage. In normal position, that is, with no roll on the carriage acting on yoke 207, the lug 188 is positioned under the rear notch on the add motor bar slide thereby blocking the add motor bar against depression but leaving the subtract motor bar free for depression. When the upward extending arm of yoke 207 is engaged by a small size control roll 209 the yoke will be rocked clockwise, looking at the machine from the rear, a sufficient distance to move the pendant lever 185 counterclockwise sufficiently to clear all notches on both motor bar stems. In other words, in this position, i. e., with a small roll 209 active, both the add and subtract motor bars are free for depression, as shown in Fig. 1. This is the condition of the machine in column 1 when the illustrated ledger form is used, where either a positive or negative old balance may be picked up and entered in the machine.

When the upper arm of yoke 207 is engaged by a medium size control roll 209, the lever 185 is moved a sufficient distance that lug 188 moves under the outer of the two forward notches in the subtract motor bar stem to block its depression, but the lever is not moved sufficiently to bring its forward lug 197 under the notch in the add motor bar slide. Accordingly in this position, that is, with the medium size control roll operative, the subtract bar is locked against depression but the add motor bar is free for depression.

When the yoke 207 is engaged by a large size control roll 209, lever 185 is rocked its full distance counterclockwise and both lugs 187 and 188 engage in their respective notches in the add and subtract motor bar stems, thus locking both motor bars against depression.

The arrangement and control of the motor bars may be summarized as follows:

No roll—locks the add motor bar (subtract motor bar released).

Small roll—unlocks both motor bars.

Medium roll—locks the subtract bar (add motor bar released).

Large roll—locks both bars.

From the foregoing it will be apparent that by utilizing various rolls 209 any desired control of motor bar depression can be obtained and that different bookkeeping forms can be accommodated by selecting different carriage rolls.

Carriage control of result keys

As previously stated, the machine is equipped with the usual function, result or operation control keys such as subtotal key, total key, non-add key, error key and repeat key, as well as a credit balance or overdraft key. The above keys, except the error and repeat keys, are what may be termed power keys because, under certain conditions, depressions of these keys causes a machine operation without the necessity of depressing either motor bar. It should also be noted that the motor bars and control or result keys are wholly independent of each other, i. e., depression of a control key may cause a machine operation but it does not depress either motor bar in so doing. This makes it possible to con-

trol certain machine functions from the motor bars, depression of which is enforced in certain columns, without having those machine functions operative upon depression of a control key.

The total and subtotal keys T and ST extend through the keyboard plates and engage lugs 220 (Fig. 7) formed on the upper side of the lever 221 pivoted at 222 and urged upwardly or clockwise by a spring 223. Lever 221 carries a slide 224 at its forward end mounted upon studs 225 for rearward and forward movements relatively to the lever, the slide being urged to the rear by a spring 226. The forward end of the slide is formed with a downward projection 227 which, when the slide is in its rearward position, overlies a stud 228 carried by the vertical clutch control member 144 so that upon downward movement of the lever 221 and its slide 224, caused by depression of a total or subtotal key, the lower projection 227 of slide 224 will engage the stud 228, if the slide is in rearward position, and lower the clutch control member 144 so as to cause a machine operation. The slide is adapted to be moved forwardly to cause the projection 227 to be ineffective under certain conditions as will be explained hereinafter. Therefore, depression of the total and subtotal keys under certain circumstances not only conditions the registering mechanism for a subtotal or total operation, as is customary, but also causes the machine to go through a cycle of operation.

The credit balance or overdraft key Cr is locked against depression by a slide as will be explained in greater detail later whenever a positive amount is contained in the registering mechanism and is free for depression whenever a negative amount is present in the registering mechanism. When depressed its lower end engages a lug 230 (Fig. 8) on the vertical slide 186 which in turn depresses lever 191 to condition the register for engagement of the subtract pinions with the actuator racks and causes a lowering of the clutch control member to start a cycle of machine operation. Accordingly, when the credit balance key is depressed it not only conditions the machine for subtraction but it also initiates a cycle of machine operation.

The lower end of the non-add key engages a lug 232 (Fig. 8) on the clutch control member 144 and thus causes a cycle of machine operation as well as conditioning the machine for a non-add operation as is usual with this key.

The error and repeat keys function in the usual manner and do not cause a cycle of machine operation.

The three control keys T, S. T. and N. A. are under control of a single carriage controlled slide 235 (Fig. 7) which extends beneath the three keys and has a series of spaced projections or lugs 236 selectively movable beneath the N. A., T and S. T. keys, so as to block depression of all of these keys when the slide is in its forward position. Adjacent its rearward end, slide 235 has a stud 240 (Fig. 7) engaging in a slot in the lower arm 241 of a crank pivoted at 222. A spring 239 is so connected at its ends to the slide 235 and to the arm 241 as to urge the stud 240 to the rearward end of the slot in the arm 241. The rear arm 242 of the crank is connected by a link 244 to a lever 245 pivoted at 203 and urged clockwise by a spring 246, the lever 245 having a stud and slot connection with a vertical sliding link 248 guided upon stud 206 for vertical movement and extending upward to a yoke 250 having an arm 251 positioned to engage control

rolls 252 on the carriage. The arrangement is such that with no roll in position the parts will assume a position with the slide 235 in a forward position where the lugs 236 thereon underlie all three control keys T, S. T. and N. A. and prevent depression of these keys. A small size roll will cause a slight rearward movement of slide 235 a sufficient distance to move one lug 236 from beneath the subtotal key to permit depression of the latter while leaving lugs 236 beneath the N. A. and T keys. A medium size roll will move slide 235 still further to the rear moving another lug 236 into position beneath the S. T. key, moving a lug out from beneath the total key and leaving a lug 236 under the N. A. key and placing another lug 236 under the subtotal key as shown in Fig. 7, thereby permitting depression of the total key only. A large size control roll will cause still further movement of the slide 235 and remove the lug 236 from beneath the non-add key, move a lug 236 into position under the total key and leaving a lug under the sub-total key, thereby permitting depression of the non-add key only.

Summarizing the effect of different size rolls upon the result or control keys, the effects may be listed as follows:

No roll—locks total, subtotal and non-add keys.
Small roll—frees subtotal key only.
Medium size roll—frees total key only.
Large size roll—frees non-add key only.

The credit balance key Cr is controlled separately by the total key as will be explained in greater detail hereafter.

From the foregoing it will be clear that any desired control of the function or control keys may be obtained for any desired program of operations to conform to any desired columnar ruling of bookkeeping sheets by merely selecting and using the proper carriage rolls in the various columnar positions of the carriage.

Total taking

At the beginning of the previous section it was mentioned that the control keys, when depressed, do not cause depression of either motor bar and it was previously mentioned that the adding motor bar has no operative connection with the means controlling the add-subtract conditioning of the registering mechanism, but it was explained that the add-subtract control means automatically restores to adding condition after each operation of the machine in which it is in subtract condition. It will, therefore, be clear that upon depression of the total or subtotal key a total or sub-total would be taken from the registering mechanism with the latter in adding condition in the absence of further provision. When the registering mechanism contains a positive total at the time the total key or sub-total key is depressed, the total or subtotal is taken with the registering mechanism in its normal adding condition, and the present machine is provided with means which will be described in the following section, which brings about the placing of the registering mechanism in subtraction condition for taking a total or subtotal when the registering mechanism contains a negative total.

Negative total indication

The present machine has a "fugitive 1" mechanism similar to that shown and described in the Butler Patent 2,118,588. In the present invention this "fugitive 1" mechanism is also used for other purposes in a manner very similar to that illus-

trated in the Butler patent not to lock the machine when a negative total is present in the registering mechanism as shown in the aforesaid patent, but to warn the operator or give an indication to him that a negative total is present in the registering mechanism.

As disclosed in the above patent, a stud 268 (Fig. 9) (stud 163 of Butler 2,118,588) is lowered whenever the registering mechanism contains a negative total. As in the Butler patent a forked arm 261 of a yoke pivoted at 262 engages this stud and is rocked clockwise whenever the total in the register becomes negative. This yoke has a forwardly extending arm 263 which is yieldingly connected by a spring 264 to the rear arm 265 (Figs. 2 and 7) of another yoke pivoted at 266 which yoke has an upstanding arm 267 which engages a horizontal slide 268 having a forward forked end 269 which engages an upwardly projecting finger 270 of the slide 224. The foregoing mechanism serves to move the slide 224 forwardly whenever the registering mechanism contains a negative total as described in the Butler patent but with a different result. As previously stated when slide 224 is moved forwardly its lower projection 227 does not engage the stud 228 on the clutch control member and accordingly depression of either the total key or subtotal key will not inaugurate a machine operation. The operator, therefore, observing that the machine does not start to cycle when he depresses the total key or sub-total key is immediately aware of the fact that there is a negative total in the registering mechanism.

In order to operate the machine to cause the true negative total to be taken from the registering mechanism it is only necessary for the operator to depress the credit balance or overdraft key while the total key or sub-total key remains latched down by the usual latch slide 165 in the control key bank. That is, it is not necessary for the operator to take spacing strokes but merely to depress a second key.

Depression of the credit balance key is normally prevented by the slide 275 underlying the top key plate and which, in normal position, engages in a notch in the stem of the credit balance key preventing depression thereof. This slide is provided with a slot 276 which, when the slide is moved forward, permits depression of the credit balance key.

As previously stated, when the registering mechanism contains a negative total the slide 224 carried by lever 221 is moved forwardly so that its lower projection clears the stud 228. Forward movement of this slide, however, moves its rear downward projection 278 directly over a stud 279 carried by one arm of a ball 280 having an upwardly extending arm 281. When the total key or sub-total key is depressed while the projection 278 is over the stud 279 because of the presence of a negative total in the register, the ball 280 is rocked counterclockwise and the arm 281, in moving to the left, engages the rear end of slide 275 and moves the latter forwardly placing its notch 276 opposite the stem of the credit balance key and permitting the latter to be depressed. The credit balance key, as previously described, lowers the clutch control members and inaugurates a cycle of machine operation. In other words, the operator has a definite indication that there is a negative total in the registering mechanism but nevertheless he is enabled to continue the operation of the machine without any further effort on his part other than to

depress a second key, the Cr key, and as previously stated, upon depression, the credit balance key conditions the registering mechanism for a subtract operation and causes the machine to operate. The total key or sub-total key, whichever was depressed prior to the depression of the credit balance key, remains latched down for the cycle of operation caused by the depression of the credit balance key and conditions the machine for total taking or sub-total taking, as the case may be, during such cycle of operation.

Proof mechanism

In most types of bookkeeping or ledger posting work it is desirable to provide some sort of proof mechanism to insure that the work has been properly entered. It will be understood that preferably a "split" platen is used as is common in this type of machine so that a ledger sheet can be removed and a new one inserted for each transaction while the proof strip can be retained in the machine and line spaced for each transaction. Before describing the details of the proof mechanism as embodied in the present invention, reference will be made to the sample form of ledger sheet and proof strip as shown in Fig. 12. In the form of ledger sheet illustrated, the entries are started with the carriage in its right or column 1 position where the previous balance or old balance of \$10.00, which is usually the last amount printed in the last column or column 3 of the previous transaction, is picked up and re-entered (column 1 of the next transaction).

In column 1 the add and subtract motor bars should be free for depression because, in this column, the pick up might be either a positive or a negative amount or old balance depending upon the previous balance. Therefore, a small size control roll 209 is active in column 1 for positioning the motor bar locking slide 235 so that either bar may be depressed. Because this column is used for the entry of a pick up of the old balance (new balance of the previous entries), no result keys should be used. Therefore, in this column no control roll for the result keys is used and, accordingly, all result keys are locked against depression. In other words, the proper entry of either positive or negative balance only is permitted or enforced. After the amount of the old balance is entered on the keyboard the machine is caused to operate in column 1 by depression of the appropriate bar. The carriage then automatically tabulates into column 2.

In column 2 the ledger form specifies an entry of the date and folio reference, and this entry requires that a non-add operation only should be permitted. Instead of permitting or enforcing operation of the machine only by depression of the non-add key a roll 133 is placed on the carriage to function as previously described to condition the register for a non-add operation of the machine in this column, and a medium size roll 209 is placed on the carriage to unlock the add motor bar in this column, but no result key control roll 252 is active in this column and all of the result keys are therefore locked. This is done because of ease of operation and to permit greater speed of operation of the machine, it being much easier to depress the add motor bar than the non-add key. After the non-add entry is made in column 2 the carriage tabulates into column 3.

In column 3, a debit column, an addition operation is required and is enforced by a roll 209 as in column 2 but there is no carriage roll 133

for causing a non-add operation and the machine is permitted to add in a normal operation. The result keys are all locked because there is no roll 252 for this column. In this column, the operator depresses the amount keys and the +M motor bar to enter a debit of \$10.00 which brings the amount in the registering mechanism up to \$20.00. Following the addition entry in column 3 the carriage tabulates to column 4, a credit column.

Usually debits and credits are not entered in the same "run" and this column would be skipped by any suitable skip tabulating mechanism designed for this type of work but not here shown.

15 If desired, the skip tabulating mechanism can be omitted or disabled and the machine operated in this column during every "run" or caused to pass through the column by taking an operation without depressing any keys.

20 Column 4 requires that a subtract operation only be permitted. In this column there is no control roll 252 so that the result keys remain locked. Because it is desired to lock the add motor bar but not the subtract motor bar, no control roll 209 is used for the motor bar locking slide. Accordingly, only the subtract motor bar is released for operation. After the subtract entry in column 4 the carriage tabulates to column 5.

25 In column 5 a small size control roll 252 is used for moving the result key slide to a position where the subtotal key is released and can be depressed by the operator to cause the machine to print the new balance of \$20.00 as a subtotal, leaving it in the register. In this column a large roll 209 is used for locking both motor bars. This completes the entries on the ledger sheet and the carriage then tabulates to column 6 or the first column on the proof strip or tally roll.

30 In this column the operator re-enters the old balance of \$10.00 by depressing the necessary amount keys and the motor bar -M opposite in sign to that depressed in column 1. In fact this is the only motor bar that is released for depression as will be explained. This, of course, is subtracted from the \$20.00 in the register and leaves \$10.00 remaining therein, and the carriage tabulates to column 7.

35 In column 6 no control roll 252 is used and accordingly all result keys are locked.

40 For proof purposes, if the amount entered in column 1 is an add item, the amount entered in column 6 on the proof strip should be a subtract item, whereas if the item entered in column 1 is a subtract item, then the amount entered in column 6 should be an add item. In other words, the entry in column 6 should be of the opposite sign of the entry in column 1. This reversal of sign of the entry in column 6 as compared with the entry in column 1 is enforced by means to be described further below.

45 With the carriage in column 7 a total is taken by depressing the T key and the total remaining in the register is printed and the register cleared. This total should equal the amount of the transaction that has been entered.

50 Fig. 12 also illustrates other entries which show possible continuations of the first line of entries and include a credit entry resulting in a credit balance followed by a debit entry resulting in another positive balance. These entries are self-explanatory and need no further discussion.

55 As previously stated, the present machine is so constructed that the operator is prevented from making an erroneous entry in any column.

nar position of the carriage and this means also enforcing the reversal of the condition of the register in columns 1 and 6, that is, the machine automatically provides that if the amount entered in column 1 is an add item or was entered by depressing the add motor bar the amount entered in column 6 on the proof strip can be entered only if entered in the opposite sign by depression of the subtract motor bar. But if, on the other hand, the amount entered in column 1 is a subtract item then the entry in column 6 should be permissible only as an add item by depression of the add motor bar. The mechanism for enforcing these proper entries will now be described.

We will consider first enforcing an addition operation in column 6 when the entry in column 1 has been a subtract entry, even though this may not be the usual situation.

Referring to Fig. 1 it will be observed that the subtract motor bar has a rearward extension 300 which, when depressed, engages a stud 301 upon the forward end of a lever 302 pivoted at 222 and having a rearward and upwardly projecting finger 303 which engages a latter lug 304 on a lever 305 pivoted on 208, which latter lever is urged counterclockwise (Figs. 4, 4^a and 6), about its pivot by a spring 304^a (Fig. 1). Lug 304 of lever 305, when the lever is in its counterclockwise position, engages a finger 306 on one arm of a yoke 307 (Figs. 4 and 6) pivoted at 308 and urged clockwise by a spring 309, thus urging a stud 311 on a second arm 312 of the yoke 307 to the right and into engagement (Fig. 6) with a depending nose 313 formed on a lever 314 pivoted at 208, said latter lever having a rearwardly projecting arm 315 adapted to engage a roller 316 on the paper carriage. The purpose of the foregoing mechanism is to set up for subsequent use, a control dependent upon the character of the entry made at the time the control is set up. Accordingly, when a roll 316 is used in column 1 and the crank or lever 314 is rocked clockwise about its pivot by this roller, the nose 313 is raised above stud 311. If the entry in this column is a negative one the lever 302 will be rocked and the lever 305 will be rocked clockwise or raised, thus permitting the ball 307 to move clockwise under the urge of its spring and place its stud 311 under the nose 313 of lever 314. This will retain the lever 314 in its clockwise position to which it was moved by roll 316. The latter lever will thus be held in its raised position while the carriage tabulates through columns 2, 3 and 4 into column 5 where the raised portion 314^a of lever 314 engages a skid 320 carried by a yoke 321 rocking the latter clockwise about its pivot 322 from the Fig. 4 position to the Fig. 5 position against the action of spring 323 and lowering the roll 324 carried by the right end of the yoke. The above stud 322 and the shafts for the control rolls 133, 209 and 252 are carried by supports adjustably secured on the stop bar 65 on the carriage. Rocking of the yoke lowers the projection 325 thereof beneath a lug 326 on the upper arm of a latch crank 327 pivoted at 328 and spring urged counterclockwise by a spring 329. The latch retains the roll in lowered position and as the carriage tabulates into column 6 roll 324 engages the motor bar control slide yoke 207 and moves the latter so as to lock the subtract motor bar and release the add motor bar, thus enforcing or permitting depression of the add motor bar only in column 6. Depression of the add motor bar in column 6 will, of

course, cause an entry in this column of opposite sign to the negative entry assumed to have been made in column 1, as was desired.

Of course, after an enforced positive entry in column 6 caused by rocking the skid 320 it is necessary to reset or return the skid clockwise. The mechanism for accomplishing this will be described after describing the operation of the above mechanisms when the entry in column 1 is a positive entry.

If the original entry in column 1 is a positive entry caused by depression of the add motor bar instead of a negative entry as was previously assumed, the entry in column 6 on the proof sheet 15 should, of course, be a negative entry and this is enforced through the foregoing mechanisms as follows:

With the same roll 316 used in column 1 the crank or lever 314 will be rocked clockwise and its 20 nose 313 will be raised as was described in connection with a negative entry in column 1. However, due to the fact that the subtract motor bar is not depressed, when a positive entry is made as it was when a negative entry was made, lever 25 302 will not be rocked clockwise to raise lever 305 to release the ball 307. Therefore, as the carriage tabulates out of column 1 and the roll 316 on the carriage leaves the arm 316, lever 314 will immediately return counterclockwise to its original 30 position. Therefore, skid 320 will not be rocked as the carriage tabulates into column 5 and, accordingly, the motor bar locking slide yoke will not be affected by roll 324. There being no roll active on the motor bar slide yoke, the 35 add motor bar is locked against depression and the subtract motor bar is free for depression. In other words, when a positive entry is made in column 1 a negative entry only will be permitted or enforced in column 6, which is the condition desired for proof entries.

As previously stated, if the skid has been rocked clockwise and is retained in its clockwise position due to a negative entry in column 1, it must be returned to raised or normal position. This is 45 accomplished as follows:

When the carriage tabulates into column 6 a pawl 335 (Fig. 5) engages the upper end of an arm 336 of a two armed lever 337 (Fig. 4^a) pivoted at 338 and urged counterclockwise by a spring 339 and moves the arm and lever slightly clockwise from the dot-dash line position to the full line position of Fig. 5. The second arm 340 of lever 337 terminates in a hooked end which 50 engages a lateral lug 341 projecting from one arm 342 of a ball 343 pivoted at 344 and urged clockwise by the same spring 339. Ball 343 has a depending arm 345 connected by a link 346 to one arm of a crank 347 pivoted at 348 and urged clockwise by a spring 349. The second arm of 55 crank 347 is adapted to engage one arm of another crank 351 shown more clearly in Fig. 13 pivoted at 352 and having a forked arm engaging stud 351^a projecting from the slide 88 which operates the tabulating mechanism and which it 60 will be recalled is operated at each machine operation. The result is that, during each operation of the machine, crank 351 is rocked first clockwise from the Fig. 13 position and is then returned counterclockwise to the Fig. 13 position. Accordingly, the crank 347 is thereby held in 65 counterclockwise position (Fig. 4^a) when the machine is at rest. During a machine operation, if the hook 340 has been withdrawn from the lug 341, the crank 347 is permitted to be moved clockwise by its spring 349 after which it 70 75

is returned the the Fig. 4^a position by crank 341. During this clockwise movement of crank 341, link 346 moves bail 343 clockwise. Accordingly, if the skid has been rocked in column 5 and the carriage has tabulated into column 6, bail 343 and its arm 342 are moved clockwise from the full line position of Fig. 5 to the dot and dash line position during the cycle of operation of the machine with the carriage in its column 6 position. During this movement of arm 342 a lug 342^a formed on the upper end thereof engages the pawl 335 and rocks the latter counterclockwise causing its forwardly projecting arm 335^a to engage the rearwardly projecting arm 327^a of latch 327 and rock the latter clockwise. This removes the projection 326 from the nose 325 of the skid yoke and allows the latter to return counterclockwise, thus raising the roll 324 to normal position where it will not engage the motor bar control arm.

During the machine operation in column 6 when the crank 341 is allowed to move clockwise a connecting link 355 (Fig. 4) restores the yoke 307 in a counterclockwise direction and allows the lateral projection 304 and the lever 305 to drop counterclockwise where it again latches the bail 307.

Briefly reviewing the mechanism for enforcing result key and motor bar depression and thereby controlling program of operations and starting with the carriage in column 1, it will be observed that crank lever 314 is moved clockwise when the carriage is in column 1 from the Fig. 4 to the Fig. 5 position by the carriage roll 318. If the subtract motor bar is depressed in column 1, lever 302 is rocked counterclockwise which in turn releases bail 307, which in turn, retains crank 314 in its clockwise position so that its raised cam portion 314^a will engage the skid 320 when the carriage arrives in column 5, thus lowering the roll 324 which, when the carriage moves into column 6, will then cause the motor bar slide yoke 207 to be moved sufficiently to lock the subtract motor bar and unlock the add motor bar. On the other hand, if the add motor bar instead of the subtract motor bar was depressed in column 1, crank 314 will be rocked clockwise by the carriage roll 318 as previously described, but lever 302 will not be rocked counterclockwise by the subtract motor bar and, therefore, crank 314 will return counterclockwise as soon as the carriage tabulates out of column 1, that is, as soon as the arm 315 of crank 314 passes from under roll 318 and, accordingly, the skid 320 will not be rocked in column 5 and the roll 324 will not be lowered to engage the motor bar slide yoke 207 in column 6, with the result that the add motor bar is locked against depression and the subtract motor bar is released for depression. In either case the motor bar released for operation when the carriage reaches column 6 is that which was not depressed in column 1, so that the entry in column 6 will necessarily be of the sign opposite to that of the entry made in column 1.

Normalizing means

One of the aims of the present invention is to provide a relatively inexpensive machine that will have particular utility in a relatively small business, which business would require a machine that could be used both as a straight adding and listing machine, and a bookkeeping or ledger posting machine. To accommodate the machine to this double use a normalizing lever is provided for normalizing all of the bookkeeping

features so that the machine may be used as an ordinary adding and listing machine capable of addition, subtraction and the accumulation of positive and true negative totals. In other words, the normalizing lever will normalize or disable the automatic carriage tabulation, carriage control of platen spacing, carriage control of non-add, carriage control of result key selection and release and automatic control of motor bar selection and release for both posting and proof entries. In other words, by a single movement of one lever the machine may be converted from an automatic ledger posting machine, in which the machine is definitely and automatically controlled in each columnar position of the carriage for a certain program, into a standard machine where any of the result keys or either motor bar can be depressed in any columnar position of the carriage.

For this purpose a normalizing lever 360 (Figs. 1 and 7) is pivoted at 361 to the stationary frame at the back of the machine. This lever 360 has the rearwardly projecting arm 96 which was previously referred to and which carries the stud 95. This stud is also adapted to engage a detent arm 363 pivoted at 364 and urged counterclockwise by a spring 365. The detent is formed with two notches in its upper edge for receiving the stud 95 and retaining the normalizing lever in either of two positions.

Carriage tabulation is disabled or normalized when the normalizing lever 360 is moved clockwise (Fig. 1) to its rearward position. In so moving the lever the stud 95 is moved forwardly and downwardly and rocks the pawl 85 clockwise or downwardly so that it is ineffective to engage the lower projection 92 on the plate 89 supporting the stop 87. In other words, the plate 89 and stop 87 are not rocked by the pawl at each cycle of machine operation.

Carriage control of platen line spacing is disabled or normalized by the same normalizer lever 360 so that instead of the platen being spaced only with the carriage in certain columnar positions, the platen will be spaced automatically with each and every machine operation regardless of the columnar position of the carriage. In other words, ordinary listing operations may be performed by the machine. The foregoing is accomplished by a stud 366 carried on the lower end of the arm 367. Stud 366 projects into a cam groove formed in one arm of a crank 367 pivoted at 364 and rocks the latter counterclockwise (Fig. 16) when the normalizing lever is moved rearward or clockwise. The lower vertical arm of crank 367 is one side member of a bail 367^a. The bail engages a tail piece 368 depending from yoke 130, the upper end of which yoke carries the arm 129 and stud 128 which engages the blade 127 and controls platen spacing as previously described. That is, when the normalizing lever 360 is moved clockwise the crank 367 and bail 367^a are cammed counterclockwise and rock the blade 127 and shaft 125 clockwise positioning the line spacing shield 120 so that the platen will be line spaced in each and every machine operation regardless of carriage position.

Carriage control of result key selection and depression is also disabled or normalized, when the normalizing lever 360 is moved clockwise, by means of a link 370 (Fig. 7) connected to the lower end of crank 367 and having a hooked end engaging a stud 371 projecting from a lever 372 urged clockwise by a spring 373 which is not strong enough to overcome either the spring 239

or the spring 246. The lower end of this lever carries a second stud 374 (Fig. 1) against which the rear end of the slide 235 is urged by a spring 375. Slide 235, it will be recalled, carries the lugs 236 that determine which result key may or may not be depressed. When the normalizing lever 360 is moved clockwise the control slide 235 is moved rearwardly sufficiently to cause all of its lugs 236 to be clear of all result keys so that any result key may be depressed regardless of the columnar position of the carriage. Because of the stud and slot connection between the crank arm 242 and the link 244, the rearward movement of the slide 235 is not resisted by the spring 246. Also, the connection between the link 370 and the stud 371 is such that the normalizing members 360, 366 and 367, when in their Fig. 1 position, do not interfere with control of the slide 235 by the carriage rolls 252.

Carriage control of motor bar release is also disabled and normalized by the normalizing lever 360. It will be recalled that if the carriage is in any columnar position where no roll 209 is engaged with the motor bar control mechanism, the lever 195 (Figs. 1 and 7) will occupy its extreme clockwise position where the add motor bar will be locked against depression but the subtract motor bar will be free for depression. When the normalizing lever 360 is moved clockwise with the carriage in a columnar position with no active control roll 209, a downwardly and forwardly extending finger 380 (Figs. 1 and 7) of the normalizing lever engages and rocks the yoke 207 (Fig. 7) that controls the motor bar controls slide to the position to which said yoke is moved by a small size control roll which, it will be recalled, conditions the mechanism so that either motor bar may be depressed. The spring 201^a and the stud and slot connection between the link 200 and the arm 202 permit the forward movement of the link 200 by the lever 387 without hindrance from a medium or large size roll 209. Also, the spring 388 connecting the rear end of link 385 to the lever 387 is sufficiently strong to overcome spring 201^a.

Carriage control of non-add operations in column 2 is also disabled or normalized by clockwise movement of lever 360 through link 385 (Fig. 7). This link carries a stud 390 that engages a vertical cipher split control arm 391 (Figs. 1 and 2) which is the third arm of the three-armed lever 137 (Fig. 2) and rocks the latter clockwise back to its normal position of Fig. 2 and stretching the spring 136 if the carriage happens to be in a position where the lever 135 is held counterclockwise from its Fig. 2 position by a roll 133.

From the foregoing description it is believed that the operation of the machine will be apparent and, therefore, no summary will be given. It will also be apparent that there has been provided a relatively inexpensive calculating machine capable of addition, subtraction and accumulation of positive and true negative totals, which machine may be used for ordinary calculating machine purposes such as adding, subtracting and printing the results on lists, and which machine is capable of performing bookkeeping operations such as ledger posting and proofs. When used for bookkeeping purposes the machine is automatically controlled so that a definite program of operation is necessarily followed by enforced depression of the proper and necessary result keys and motor bars. In other words, proper operation of the machine for book-

keeping purposes is assured even though the operator may be either inexperienced and/or an occasional operator of the machine.

It will be apparent to those skilled in the art that, although the invention is shown as being applied to a Burroughs type of machine, the invention may be embodied in other types of machines and, furthermore, that variations and details of construction may be followed without departing from the spirit and scope of this invention as defined in the claims.

I claim:

1. A machine of the class specified, having a motor operated driving means, drive control means for causing said motor operated driving means to drive said machine through cycles of operation, differential actuator means, a registering mechanism cooperable with said differential actuator means for entry of amounts into and withdrawal of totals from said registering mechanism, total-taking control means to cause said registering mechanism to control said differential actuator means in total-taking cycles of operation of said machine, addition-subtraction control means to condition said registering mechanism for operations of either positive or negative algebraic character, means controlled by said registering mechanism in accordance with the algebraic character of the total contained therein to enable said total-taking control means when conditioned for total taking with a total of one algebraic sign in said registering mechanism to condition said motor operated drive means to give said machine a cycle of operation but to disable said total-taking control means from conditioning said motor operated means while said registering mechanism contains a total of the opposite algebraic sign, and manually operable means for conditioning said addition-subtraction control means to an operation of said opposite algebraic character and conditioning said motor operated driving means to give said machine a cycle of operation to take the total of said opposite algebraic character from said registering mechanism.

2. A machine of the class specified, having a motor operated driving means, drive control means for causing said motor operated driving means to drive said machine through cycles of operation, differential actuator means, a registering mechanism cooperable with said differential actuator means for entry of amounts into and withdrawal of totals from said registering mechanism, total-taking control means to cause said registering mechanism to control said differential actuator means in total-taking cycles of operation of said machine, addition-subtraction control means to condition said registering mechanism for operations of either positive or negative algebraic character, manually operable means for conditioning said addition-subtraction control means for an operation of one algebraic character and conditioning said drive control means to cause said motor operated driving means to give said machine a cycle of operation, means normally preventing operation of said manually operable means, means controlled by said registering mechanism in accordance with the algebraic character of the total contained therein to enable said total-taking control means when conditioned for total-taking with a total of the opposite algebraic character in said registering mechanism to condition said drive control means to cause said motor operated drive means to give said machine a cycle of operation with said addi-

tion-subtraction control means conditioned for an operation of said opposite algebraic character but to disable said total-taking control means from conditioning said drive control means while said registering mechanism contains a total of said one algebraic character, and means controlled by said total-taking control means when conditioned for total taking to disable said preventing means.

3. A machine of the class specified, having a motor operated driving means, drive control means for causing said motor operated driving means to drive said machine through cycles of operation, differential actuator means, a registering mechanism cooperable with said differential actuator means for entry of amounts into and withdrawal of totals from said registering mechanism, total-taking control means to cause said registering mechanism to control said differential actuator means in total-taking cycles of operation of said machine, addition-subtraction control means to condition said registering mechanism for operations of either positive or negative algebraic character, manually operable means for conditioning said addition-subtraction control means for an operation of one algebraic character and conditioning said drive control means to cause said motor operated driving means to give said machine a cycle of operation, means normally preventing operation of said manually operable means, and means controlled by said registering mechanism in accordance with the algebraic character of the total contained therein to enable said total-taking control means when conditioned for total-taking with a total of the opposite algebraic character in said registering mechanism to condition said drive control means to cause said motor operated drive means to give said machine a cycle of operation with said addition-subtraction control means conditioned for an operation of said opposite algebraic character but to disable said total-taking control means from conditioning said drive control means while said registering mechanism contains a total of said one algebraic character and to enable said total-taking control means when conditioned for total taking to disable said preventing means.

4. A machine of the class specified, having a motor operated driving means, control means for causing said motor operated driving means to drive said machine through cycles of operation, differential actuator means, a registering mechanism cooperable with said differential actuator means for entry of amounts into and withdrawal of totals from said registering mechanism, total-taking control means to cause said registering mechanism to control said differential actuator means in total-taking cycles of operation of said machine, addition-subtraction control means to condition said registering mechanism for operations of either positive or negative algebraic character and normally conditioned for operations of one algebraic character, manually operable means for conditioning said addition-subtraction control means for an operation of said opposite algebraic character and conditioning said motor operated driving means to give said machine a cycle of operation, means normally preventing operation of said manually operable means, and means controlled by said registering mechanism in accordance with the algebraic character of the total contained therein to enable said total-taking control means when conditioned for total taking with a total of said one

algebraic sign in said registering mechanism to condition said motor operated drive means to give said machine a cycle of operation but to disable said total-taking control means from conditioning said motor operated means while said registering mechanism contains a total of said opposite algebraic sign and to enable said total-taking control means when conditioned for total taking to disable said preventing means.

5. A machine of the class specified, having a motor operated driving means, drive control means for causing said motor operated driving means to drive said machine through cycles of operation, differential actuator means, a registering mechanism cooperable with said differential actuator means for entry of amounts into and withdrawal of totals from said registering mechanism, total-taking control means normally free regardless of the algebraic character of the total contained in said registering mechanism to be manually conditioned to cause said registering mechanism to control said differential actuator means in total-taking cycles of operation of said machine, addition-subtraction control means to condition said registering mechanism for operations of either positive or negative algebraic character, means controlled by said registering mechanism in accordance with the algebraic character of the total contained therein to enable said total-taking control means when conditioned for total taking with a total of one algebraic sign in said registering mechanism to condition said motor operated drive means to give said machine a cycle of operation but to disable said total-taking control means from conditioning said motor operated means while said registering mechanism contains a total of the opposite algebraic sign, and manually operable means for conditioning said addition-subtraction control means for an operation of said opposite algebraic character and conditioning said motor operated driving means to give said machine a cycle of operation to take the total of said opposite algebraic character from said registering mechanism.

6. A machine of the class specified, having a motor operated driving means, drive control means for causing said motor operated driving means to drive said machine through cycles of operation, differential actuator means, a registering mechanism cooperable with said differential actuator means for entry of amounts into and withdrawal of totals from said registering mechanism, total-taking control means to cause said registering mechanism to control said differential actuator means in total-taking cycles of operation of said machine, addition-subtraction control means to condition said registering mechanism for operations of either positive or negative algebraic character, means controlled by said registering mechanism in accordance with the algebraic character of the total contained therein to enable said total-taking control means when conditioned for total taking with a total of said one algebraic sign in said registering mechanism to condition said motor operated drive means to give said machine a cycle of operation but to disable said total-taking control means from conditioning said motor operated means while said registering mechanism contains a total of the opposite algebraic sign, means to latch said total-taking means in total-taking condition when so conditioned, means operable automatically in a machine cycle to release said total-taking means, and manually operable means for conditioning said addition-subtraction control

means for an operation of said opposite algebraic character and conditioning said motor operated driving means to give said machine a cycle of operation with said total-taking means in total-taking condition.

7. A machine of the class specified, having a motor operated driving means, drive control means for causing said motor operated driving means to drive said machine through cycles of operation, differential actuator means, a registering mechanism cooperable with said differential actuator means for entry of amounts into and withdrawal of totals from said registering mechanism, total-taking control means to cause said registering mechanism to control said differential actuator means in total-taking cycles of operation of said machine, addition-subtraction control means to condition said registering mechanism for operations of either positive or negative algebraic character, manually operable means for conditioning said addition-subtraction control means for an operation of one algebraic character and conditioning said drive control means to cause said motor operated driving means to give said ma-

chine a cycle of operation, means normally preventing operation of said manually operable means, means controlled by said registering mechanism in accordance with the algebraic character of the total contained therein to enable said total-taking control means when conditioned for total taking with a total of the opposite algebraic character in said registering mechanism to condition said drive control means to cause said motor operated drive means to give said machine a cycle of operation with said addition-subtraction control means conditioned for an operation of said opposite algebraic character but to disable said total-taking control means from conditioning said drive control means while said registering mechanism contains a total of the opposite algebraic character, means controlled by said total-taking control means when conditioned for total taking to disable said preventing means, means to retain said total-taking means in total-taking condition after being so conditioned, and means operable automatically in a machine cycle to restore said total-taking means to normal.

ERNEST RACZ.
